UNITED STATES PATENT OFFICE

BERNARD W. STRAW, OF MOUNT AIRY, MARYLAND, ASSIGNOR TO AUTOMATIC BAL-
LAST SPREADER CORPORATION, OF WILMINGTON, DELAWARE, A CORPORATION OF
DELAWARE

MEANS FOR DISTRIBUTING BALLAST

Application filed November 21, 1927. Serial No. 234,853.

This invention relates to ballast distributing means, and more particularly to means for discharging or spreading ballast in the cross-tie cribs of a railway track.

5 In forming a track ballast cross-section a particular amount of ballast is required in the cross-tie cribs. For example, in certain instances it is desired to discharge sufficient ballast into said cribs so that the depth of
10 the ballast extends from the sub-grade to within approximately two inches below the upper surface of the cross-ties. In other instances it is desirable to bring the "height" of the ballast approximately half way up the
15 sides of the cross-ties only. Much expense and labor have heretofore been expended in thus distributing ballast, due to the fact that it has been necessary to manually handle the ballast so as to insure its proper depth
20 in the cross-tie cribs.

One of the objects of the present invention is to provide novel means for discharging ballast into the cross-tie cribs of a railway track.

25 Another object of the invention is to provide means for distributing ballast in such a manner as to provide the desired depth of ballast in the cross-tie cribs of a track.

Another object is to provide means adapted
30 to be associated with a ballast carrier for distributing ballast in a predetermined manner in a cross-tie crib.

A further object is to provide means of the above character which are adapted to be
35 operatively and detachably associated with a ballast carrier, such as a hopper car.

Another object is to provide means for dis-
40 charging ballast into the cross-tie cribs, said means being adapted for use in conjunction with a ballast spreading or distributing pan.

Another object of this invention is to pro-
45 vide a cross-tie crib ballast dresser so constructed that ballast may be distributed at the required points and in the required amounts in the cross-tie cribs, the dresser being automatic in action.

Another object is to provide a cross-tie
50 crib ballast dresser which is so constructed that the carrier with which the dresser is operatively associated may be moved in either

direction along the track, without injury to the dresser structure.

A further object is to provide a cross-tie crib dresser which is so constructed that ballast may be distributed in the portion of the cross-tie cribs between the rails, and in those portions of the cribs intermediate the rail and the outer ends of the cross-ties. 55

A still further object is to provide novel means for securing the dresser to the ballast carrier. 60

The invention is capable of receiving a variety of mechanical expressions, one of which is shown in the accompanying drawings, but it is to be expressly understood that the drawings are for purposes of illustration only and are not designed as a definition of the limits of the invention, reference being had to the appended claims for this purpose. 65

Referring to the drawings, wherein like reference characters refer to like parts throughout the several views, 70

Figure 1 is a side elevation of a portion of a hopper car to which is operatively connected one form of the structure constituting the subject matter of the present invention. 75

Figure 2 is a transverse sectional view of the hopper car shown in Fig. 1, the structure of the present invention being shown attached thereto in side elevation. 80

Figures 3, 4 and 5 are detail views, partly in section and partly in elevation, illustrating the operation of the structure of the present invention; and

Figure 6 is a perspective view of one form of dresser embodying the present invention. 85

The structure constituting the subject matter of the present invention is particularly adapted for use in combination with a railway hopper car of the usual type, but the same may be employed in combination with the hopper and ballast car disclosed in my co-pending application Serial No. 175,339, filed March 14, 1927. 90

Referring more particularly to Figs. 1 and 2, a railway hopper car 7, provided with the usual hopper 8 and hopper door 9, has associated therewith ballast distributing and dressing means, which in the present instance comprise a ballast distributing pan and a 100

ballast dresser for delivering ballast into the cross-tie cribs.

The form of ballast distributor illustrated in the drawings comprises a substantially rectangular pan structure 10 provided with side walls 11 (Fig. 3) and detachable end walls 12. The distributor 10, which extends transversely of the car and rails, may be operatively connected to the hopper car by suitable means preferably comprising hook-shaped bars 13 and chains 14, the bars being adapted to hook over the top edges of the car sides and the lower ends of the chains being secured to the upper corners of the end walls 12 in any convenient manner. The upper ends of the chains 14 are secured to a lever 15 pivotally carried by said bar 13. By adjusting the angular position of lever 15, the height of the distributor 10 above the top of the rails 16 may be readily varied. The lever 15 is preferably held in adjusted position by means of a chain 17 adapted to engage with a selected link of one of the chains 14. The distributor is thus removably secured immediately below the hopper 8, in a position to receive ballast from said hopper when the door 9 is open.

The bottom 18 of the distributor is provided with one or more longitudinally extending openings 19 (Fig. 5) which are adapted to be closed by means of sliding doors 20. These doors may be operated from the side of the car, as by means of suitable levers 21. Each of the detachable end walls is preferably provided with a sliding door 22 adapted to be actuated by means of a lever 23 to which is pivotally secured a link 24, the lower end of said link being secured in any suitable manner to the door 22.

The sliding doors 20 in the bottom of the distributor 10 control the discharge of ballast from the distributor to the crib dresser (presently to be described) while doors 22 in the opposite end walls of the distributor control the discharge of ballast onto the ballast shoulder and/or center ditch.

Means are provided for receiving and distributing the ballast discharged through the openings 19, whereby the ballast is deposited throughout each cross-tie crib, said means acting automatically to prevent the discharge of ballast where it is not needed. In the form shown, said means comprise a center dresser 25 (Fig. 6) and a pair of outer dressers 26, 27, the outer dressers being substantially duplicates.

The center dresser 25, which controls the discharge of ballast to that portion of the cross-tie cribs between the rails, comprises an upper plate 28 adapted to extend transversely of the rails and bent longitudinally at 29 to form a downwardly projecting portion 28^a. Pivoted connected to the lower edge of the portion 28^a, as by means of a suitable number of hinges 30, is a substantially flat plate 31

adapted to form a continuation of portion 28^a. Hinges 30 are so mounted on the under surfaces of plates 28 and 31 that the latter cannot swing upwardly out of the plane of portion 28^a, but is capable of free pivotal movement in the opposite direction. The end edges of plate 31 may converge inwardly to clear the rails 16.

Pivoted to the lower edge of plate 31 is another plate 32 which is substantially the same length as the lower edge of plate 31, as shown most clearly in Fig. 2. Hinges 33 which are provided for securing the plate 32 to plate 31 are so formed that plate 32 can swing freely in either direction. Pivoted to the lower edge of plate 32, as by means of hinges 34, are a plurality of plates 35 which are preferably of less width than plates 32. In the form shown, three plates 35 are employed, but it is to be understood that the number of these plates may be varied as desired.

The center dresser, constituted by plates 28, 31, 32 and 35, is provided with means for removably attaching it to the ballast distributor. For this purpose two laterally spaced and substantially parallel bars 36 are adjustably secured adjacent the opposite ends of the upper surface of plate 28, the bars extending substantially at right angles to the plate. Pivoted attached to each end of each of said bars is a supporting member 37 having a hook portion 37^a adapted to engage the top edge of one of the side walls 11 of the distributor 10, whereby the center dresser may be quickly installed or removed. The amount of ballast discharged by the center dresser may be varied by changing the position of the plates relative to openings 19. For this purpose, bars 36 are provided with a plurality of openings 38 through which extend suitable members, such as bolts 39, for adjustably securing the plates to said bars. Means are provided for controlling the discharge of ballast into that portion of the cross-tie crib between the ends of the ties and adjacent rail. For this purpose the present invention includes a pair of structures quite similar to the center dresser described above and differing therefrom primarily in length only. Each of the outside dressers preferably comprises an upper bent plate 40 pivotally connected, as by means of suitable hinges 30, to a plate 41, the lower edge of the latter being connected to a plate 42, and hinged to the lower edge of plate 42 is an additional plate 43. Two substantially parallel bars 44 which extend transversely of plate 40 are secured, as by means of bolts 39, to the upper surface of the horizontally disposed portion of plate 40. Attached to the outer ends of these bars are hook-shaped hangers 45 and 46 for connecting the outside dressers to the distributor. Hangers 46 are preferably of less length than hangers 37 and 45, in order

that the former may engage the lower edge 47 of suitable openings 48 provided adjacent the outer ends of the side walls 11 of the distributor. The openings 48 also constitute hand holes to facilitate handling of the distributor 10.

The operation of the device is shown more clearly in Figs. 3, 4 and 5. By opening door 9 of the carrier, which is moving along the track, ballast is discharged into distributor 10. Upon opening sliding doors 20 of the distributor ballast falls by gravity onto the plates of the center and outer dressers. The dressers are so constructed that when the lower plates 35 and 43 engage the top of a cross-tie 47, the hinged plates assume angular positions temporarily arresting downward flow of the ballast by permitting it to assume an angle of repose. The angle of repose, of course, varies with the nature and form of the particular ballast used. As the carrier and dressers continue their movement, plates 35 and 43 fall by gravity into the crib, and, if the level of the ballast in the crib is below the desired height, the plates will assume angular positions affording an effective slope which is greater than the slope or angle of flow of the ballast, thereby permitting the proper amount of the latter to discharge into the crib. As the plates move out of the crib onto the next adjacent cross-tie, their relative angular positions are again changed so that the delivery of ballast is stopped. If the next adjacent crib contains the proper amount of ballast, the plates will assume such an angle therein that no ballast will be discharged. If one portion of the crib between the rails contains sufficient ballast while another portion or portions thereof are below the desired level, the plates 35 automatically act to control or prevent the discharge of ballast to said portions as may be necessary. The discharge of ballast into a crib is not controlled, therefore, by a single high point in the crib.

When it is desired to vary the height or amount of ballast discharged into the cribs, the plates of each dresser are moved relative to the bars 36 and 44; and if a different character of ballast is used, so that the slope of discharge of the same is different from that previously used, the position of the plates relative to bars 36 and 44 may be likewise changed to insure that a proper amount of the ballast will be distributed. The outer dressers 26 and 27 operate in a manner similar to the center dresser 25. It is unnecessary to provide the opposite ends of plates 39, 40, 30, 31 with any upwardly extending portions or flanges to prevent ballast from being discharged over the ends of the plates, for it has been found that only a slight amount of ballast escapes in this way.

The direction of movement of the carrier may be reversed at any time without damage to the dressers. The hinged plates will move

over the upper surface of the cross-ties or over an obstruction, such as a misplaced tie, without danger of injury to the structure, as is clearly shown in Fig. 5.

My invention provides means for distributing the ballast to the cross-tie cribs of a track in the desired amount and in the desired positions. The device is simple in construction and automatic in operation. It may be readily applied to a ballast carrier of the hopper car type without the necessity for any structural changes in the latter. This is of importance since the carrier may then be used as an ordinary hopper car when it is desired, thereby avoiding the necessity for hauling empty cars great distances. Heavy expense incident to manual handling of the ballast is avoided.

Having now described my invention, what I claim is:—

1. In combination, a ballast carrier, a distributor operatively connected to said carrier, and dresser means movable with said carrier and distributor for discharging ballast into the cross-tie cribs of a railway track.

2. In combination with ballast carrying and distributing means, dresser means for controlling the discharge of ballast into the cross-tie cribs of a railway track, and means for operatively connecting said dresser means to said first named means.

3. In combination with a ballast carrier, means for depositing ballast in the cross-tie cribs of a railway track, said means comprising a plurality of pivoted members adapted automatically to control the delivery of ballast to said cross-tie cribs.

4. In combination with a ballast distributor, a center dresser and a pair of outside dressers for controlling the discharge of ballast into the cross-tie cribs of a railway track.

5. In combination with ballast carrying means, means including flexible means for distributing ballast received from the carrying means into the cross-tie cribs of a track on which said carrying means is movable, said carrying means and said flexible means being relatively positioned to enable ballast to be discharged by gravity from said carrying means and to flow by gravity over said flexible means.

6. In combination with ballast carrying and distributing means, dressing means including a plurality of members relatively movable angularly for delivering ballast into the cross-tie cribs of a railway track.

7. In combination with ballast carrying and distributing means, dresser means for controlling the discharge into the cross-tie cribs of a railway track the ballast received from said first named means, and means for permitting the position of said dresser means to be adjusted relative to said carrying and distributing means.

8. In combination with a hopper car, a distributor operatively connected to said car to receive ballast therefrom, dresser means operatively connected to said distributor for depositing ballast into the cross-tie cribs of a railway track on which said car is moved, and means for controlling the discharge of ballast from the distributor to said dresser means.
9. In combination with ballast carrying and distributing means, dresser means including a plurality of pivotally connected members, and means for controlling the flow of ballast from said first named means to said dresser means.
10. In combination with ballast carrying and distributing means, dresser means for controlling the discharge of ballast to the portion of the cross-tie crib of a railway between the rails, dresser means for controlling the discharge of ballast to the portion of the cross-tie crib between the ends of the cross-ties and the respectively adjacent rails, and means for controlling the discharge of ballast to said dressers.
11. A ballast spreader and dresser comprising a plurality of hinged members, one of said members being formed in sections.
12. A ballast dresser comprising a plurality of pivotally connected plates, and adjustable supporting means for said plates.
13. A ballast dresser comprising flexible means adapted to be moved over the cross-ties of a railway track and to be actuated by said cross-ties.
14. A ballast dresser comprising a plurality of movably connected rigid elements, said elements being adapted to be moved along a railway track and the lowermost one of said elements being adapted to engage the tops of the cross-ties of said track.
15. A ballast dresser comprising a plurality of pivotally connected plates, and means for operatively connecting said plates to a ballast carrier, one or more of said plates being adapted to assume an angular position relative to the carrier.
16. In combination with a railway hopper car, ballast dressing means operatively connected to said car for delivering ballast into the cross-tie cribs of the track along which said car is moved, said dressing means including a plurality of movably connected members, one of said members being adapted to engage the tops of the cross-ties and to swing to either side of the vertical.
17. The method of discharging ballast into a cross-tie crib which consists in continuously applying ballast to a sloping sheet, and intermittently changing the slope of said sheet so as to cause the ballast passing over said sheet to intermittently assume the angle of repose.
18. The method of distributing ballast on a ballast cross-section which consists in causing ballast to flow by gravity down an incline comprising a plurality of flexibly connected plates, and intermittently changing the relative angular relation of said plates to vary the amount of ballast discharged.
19. The method of distributing ballast on a ballast cross-section which consists in supporting ballast above said section, moving the ballast relative to said section, and employing the irregularities in the surface over which the ballast is moved to vary the angular position of the support for the ballast, whereby the amount of ballast distributed is controlled.
20. In combination with ballast carrying and distributing means, flexible dresser means operatively connected to said carrying means, said flexible means being adapted to engage the surface on which the ballast is to be deposited, and being adapted to substantially follow the irregularities of said surface, whereby the angular position of said flexible means is varied and the amount of ballast distributed is controlled.
21. In combination, a ballast carrying car, and means movable with said car for depositing ballast in the cross-tie cribs of a railway track, said means being adapted to engage with and be actuated by said cross-ties.
22. In combination, a ballast carrying car, and means movable with the car for depositing ballast to the roadbed of a railway track, said means being engageable with the railway track cross-ties and the portions of the roadbed intermediate said cross-ties for controlling the delivery of ballast to the roadbed.
- In testimony whereof I affix my signature.
- BERNARD W. STRAW.
